UNITED STATES PATENT OFFICE.

CHARLES H. BARTLETT, OF ARLINGTON, MASSACHUSETTS.

DESIGN FOR A HASSOCK.

SPECIFICATION forming part of Design No. 19,186, dated July 2, 1889.

Application filed May 13, 1889. Serial No. 310,642. Term of patent 14 years.

To all whom it may concern:

Be it known that I, CHARLES H. BARTLETT, of Arlington, in the county of Middlesex and State of Massachusetts, have invented and produced a new and original Design for Hassocks, of which the following is a specification.

The design consists in the shape of the top and sides of the hassock shown in the accompanying drawings, in which—

- 10 Figure 1 represents a top view, and Fig. 2 a perspective view, of a hassock embodying my design. Fig. 3 is a top view of a slightly modified form.

The top of the hassock is composed of pieces 15 $a a' a'$, so formed that the seams 2 2 3 3 at their adjoining edges form ogee curves, said curves intersecting each other at the center of the top. The sides of the hassock are formed to present four salient curves 4 4 5 5, 20 separated by re-entrant angles. The curves 4 4, when viewed from the top, present continuations of the ogee-curved seams, said

seams and the curves 4 4 making the top pieces $a a$ approximately oval, as shown in Fig. 1, or approximately circular, as shown in Fig. 3. The side curves 5 5, as shown in Figs. 1 and 2, are longer than the curves 4 4.

The chief features of my design are, first, the shape of the top pieces, said top pieces having an ogee curvature, and, secondly, the curved sides, two of which constitute continuations of the ogee seams.

I claim—

The design for a hassock, substantially as herein shown and described. 35
In testimony whereof I have signed my name to this specification, in the presence of two subscribing witnesses, this 9th day of May, A. D. 1889.

CHARLES H. BARTLETT.

Witnesses:

K. E. BROWN,
A. D. HARRISON.
